DESIGN FOR A BREAD SLICING BOARD

Willis H. Wagner, Kansas City, Mo.

Application February 13, 1943, Serial No. 109,535

Term of patent 3½ years

To all whom it may concern:

Be it known that I, Willis H. Wagner, a citizen of the United States, residing at Kansas City, in the county of Jackson and State of Missouri, have invented a new, original, and ornamental Design for a Bread Slicing Board, of which the following is a specification, reference being had to the accompanying drawing, forming part thereof, in which:

Fig. 1 is a perspective view of the board, showing the new design;

Fig. 2 is a side elevational view;

Fig. 3 is a top plan view; and

Fig. 4 is an end elevational view thereof.

I claim:

The ornamental design for a bread slicing board, substantially as shown.

WILLIS H. WAGNER.
